CLAIM

The ornamental design for a footwear outsole, as shown and described.

DESCRIPTION

FIG. 1 is a perspective view of a footwear outsole showing my new design;

FIG. 2 is a right side elevational view thereof;

FIG. 3 is a left side elevational view thereof;

FIG. 4 is a bottom plan view thereof;

FIG. 5 is a top plan view thereof;

FIG. 6 is a front elevational view thereof; and,

FIG. 7 is a rear elevational view thereof.

The broken-line in FIGS. 1, 4 and 6 defines the interior boundary of the design. None of the broken lines or the areas within them form any part of the claim.

The broken line showing the remainder of the footwear in FIGS. 1-3 and 5-7, illustrates the portion of the design that forms no part of the claim.
